UNITED STATES PATENT OFFICE.

LOUIS T. FREDERICK, OF WILKINSBURG, PENNSYLVANIA, ASSIGNOR TO WESTINGHOUSE ELECTRIC & MANUFACTURING COMPANY, A CORPORATION OF PENNSYLVANIA.

STREAM-LINED STRUT.

1,403,310.

Specification of Letters Patent. Patented Jan. 10, 1922.

Application filed June 17, 1918. Serial No. 240,285.

To all whom it may concern:

Be it known that I, LOUIS T. FREDERICK, a citizen of the United States, and a resident of Wilkinsburg, in the county of Allegheny 5 and State of Pennsylvania, have invented a new and useful Improvement in Stream-Lined Struts, of which the following is a specification.

My invention relates to improvements in stream-lined struts, and it has for its primary object the construction of a strut of hollow rectangular section stream-lined with one or more sections of properly shaped tubes comprising superimposed laminations 15 of impregnated sheet material.

Heretofore, it has been customary, in making struts of wood, to employ a single strip or rod of wood and to apply a suitable stream-lining thereto, this necessitating careful selection and shaping of the wood and consequent employment of skilled labor. In view of this, another object of my invention is to construct a stream-lined strut in which several strips of wood may be employed to 25 form the strut and thus greatly decrease the necessity of employing wood as clear and free of blemishes as that usually required. This, therefore, makes possible the use of wood which previously has been discarded 30 as waste material in aeroplane construction.

Since any reduction in weight, without the sacrifice of strength of the structural elements used in aeroplane construction, is 35 advantageous, another object of my invention is to construct a built-up strut of hollow rectangular section which shall be of less weight and have as great strength as ordinary struts of solid section.

40 A further object of my invention is to construct a strut which will be less liable to be seriously damaged by bullets and small shell fragments.

A still further object of my invention is to 45 construct a strut of hollow rectangular section adapted to be stream-lined with lengths of properly shaped tubes and to join and support the tubes by means of blocks disposed at suitable intervals along the strut.

50 With these and other objects in view, a better understanding of my invention may be had by reference to the drawings in which Fig. 1 is a transverse sectional view of a stream-lined strut embodying my invention; Fig. 2 is a side elevation, partly in section,

of the strut shown in Fig. 1; Fig. 3 is a side elevation, on a smaller scale, of a strut constructed in accordance with my invention, parts being broken away, showing several supporting blocks and the joined ends of the 60 short lengths of the stream-lining enclosing the strut.

In practising my invention, I may fasten four strips of wood, or other suitable material, such as impregnated sheet material, together to form a hollow rectangular strut. 65 About the strut, thus formed, a suitable stream-lining may be applied which may have properly shaped supporting elements or blocks interiorly disposed at intervals along 70 its length for the purpose of supporting the stream-lining or as a means for fastening the stream-lining to hold it in place when several lengths of it are used in completing the structure.

75 Referring to the drawings, the parallel strips 1 are fastened, by any suitable means, to the narrow parallel strips 2 to form a hollow rectangular strut. In stream-lining the strut, either of the narrower strips 2 that 80 are fastened to the edges of the wider strips 1 may be considered as the front, and blocks 3 may be fastened thereto at intervals along the strut. Blocks 4 are fastened to the wider parallel strips 1 and blocks 5 are fastened to the rear of the strut forming the trailing edge. The blocks 3, 4 and 5, thus positioned about the strut, are preferably 85 short and have substantially the same spacing along the strut. The assembled blocks 90 conform to the shape of the stream-lining 6 which surrounds the strut and the blocks. The stream-lining 6, which encloses the strut throughout its entire length, may be in one piece or of short lengths which have their 95 abutting ends 7 fastened to the blocks 3, 4 and 5 by screws 8, or other suitable means.

In order to be efficient, as a structural element in aeroplanes, a strut should have its greatest cross-sectional strength in the axis 100 of its direction of movement when the plane is in flight which is one reason for the design of the type of strut disclosed. The employment of rods and tubes of circular or rectangular cross section as struts involves 105 waste of material because, in order to secure sufficient strength in one direction, a superfluous amount of material must be used in the other. Struts of elliptical cross section overcome this difficulty to a certain ex- 110

tent but they require careful work in properly shaping them. Furthermore, a one-piece strut, if struck by a bullet or shell fragment, is more likely to be vitally damaged than is a built-up strut of the type set forth. A strut constructed in accordance with my invention therefore overcomes all of the difficulties described above and may also be easily and quickly constructed by 10 persons who are unskilled in the art.

Obviously, minor changes may be made in constructing a strut embodying my invention without departing from the spirit of the invention, and I desire, therefore, that 15 no limitations shall be imposed except such as are indicated in the appended claims.

I claim as my invention:

1. A strut of hollow, rectangular section stream-lined with short lengths of tubing, 20 having a proper stream-line shape, placed end to end to enclose the strut throughout its entire length.

2. A hollow strut built up of longitudinal

strips having supporting elements disposed at intervals thereon and stream-line tubes 25 disposed end to end about the strut and secured to the supporting elements.

3. A strut of hollow, rectangular section having supporting elements disposed at intervals thereon and stream-line tubes disposed end to end about the strut and secured to the supporting elements. 30

4. A strut of hollow, rectangular section having supporting elements disposed at intervals thereon and stream-line tubes disposed end to end about the strut and secured to the supporting elements, the inner faces 35 of the supporting elements closely engaging the outer surfaces of the strut and the outer faces of the supporting elements coming in close contact with the stream-line tubes. 40

In testimony whereof I have hereunto subscribed my name this 31st day of May, 1918.

LOUIS T. FREDERICK.
